(57) CLAIM

The ornamental design for a dispenser, as shown and described.

DESCRIPTION

FIG. 1 is a front view of a dispenser of the present invention; FIG. 2 is a left side view thereof;

FIG. 3 is a back view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof, shown in environmental use; and,

FIG. 9 is another perspective view thereof, shown in environmental use.

The dot-dot-dash broken lines in the figures illustrate environmental subject matter that form no part of the claimed design.
